UNITED STATES PATENT OFFICE.

HARVEY HALL, OF PAONIA, COLORADO.

CROSS-LINE BUCKLE.

961,347.

Specification of Letters Patent. Patented June 14, 1910.

Application filed March 8, 1909. Serial No. 481,879.

To all whom it may concern:

Be it known that I, HARVEY HALL, citizen of the United States, residing at Paonia, in the county of Delta and State of Colorado, 5 have invented certain new and useful Improvements in Cross-Line Buckles, of which the following is a specification.

This invention comprehends certain new and useful improvements in buckles of that 10 type designed particularly for use on harness in connecting the cross line to the long line, and the invention has for its object an improved device of this character which embodies to a marked degree the characteristics of simplicity, durability and strength, and which includes a peculiar arrangement of parts whereby the straps passing through the buckle serve to maintain the tongues effectually in engagement with the 15 long line in order to connect the cross line thereto, the buckle being susceptible of being readily manipulated to adjust the cross line upon the long line as required.

With this and other objects in view that 20 will more fully appear as the description proceeds, the invention consists in certain constructions and arrangements of the parts that I shall hereinafter fully describe and then point out the novel features thereof in 25 the appended claims.

For a full understanding of the invention and the merits thereof and to acquire a knowledge of the details of construction, 30 reference is to be had to the following description and accompanying drawing, in which:

Figure 1 is a perspective view illustrating the application of my improved cross line buckle; Fig. 2 is a longitudinal section 35 thereof; and Fig. 3 is a perspective view of the buckle detached.

Corresponding and like parts are referred to in the following description and indicated in all the views of the drawing by the same 40 reference characters.

My improved device consists essentially of a buckle frame that is preferably substantially rectangular in top plan view and that comprises spaced side bars 1 connected 45 by transverse end bars 2 and 3. In the present instance this buckle frame is formed from a single length of stout wire and the side bars 1 are correspondingly looped or coiled in proximity to the end bar 2 to constitute bearings 4, while intermediate of 50 the bearings and the opposite end bar 3, the side bars are formed with transversely alining similar open crimps 5, which face on one side of the buckle frame for a purpose to be presently disclosed. 55

6 designates a bail which is mounted on said side of the buckle frame and which is preferably formed from a strip of heavy wire bent to form a cross bar 7 at the swinging end of the bail and transversely 60 spaced short side bars 8. The ends of the wire are correspondingly inwardly disposed at the opposite end of the bail and substantially in the plane thereof, as indicated at 9, and are journaled in the respective bearings 65 4, the said ends projecting inwardly beyond the side bars 1 to form in effect a cross bar at the pivoted end of the bail and having their extremities correspondingly out-turned 70 in angular relation to the plane of the bail 75 to constitute strap engaging tongues 10. The tongues 10 project through the buckle frame and are arranged on the opposite side thereof from the bail and are inclined in operative position toward the end bar 2, in which 80 position the cross bar 7 at the swinging end of the bail is seated in the crimped portions 5, as best seen in Fig. 2.

In the practical use of a buckle constructed in accordance with my invention, the rear 85 end of the cross line, A, is passed around the cross bar at the pivoted end of the bail 6 and engaged with the tongues 10, which latter project outwardly therethrough in order to engage the long line, B. The long 90 line, B, is passed upwardly between the end bar 2 and the cross bar at the pivoted end of the bail 6 and is then passed downwardly through the bail, whereby to be looped over 95 said cross bar and the tongues 10 carried thereby (see Fig. 2). The long line and cross line extend forwardly beneath the cross bar 7 and between the same and the adjacent end bar 3 of the buckle frame and are attached to the bits of the horses in the 100 customary manner. The stiffness and thickness of these two straps, together with the tension exerted thereon serves to maintain the cross bar 7 seated in the crimped portions 5. This causes the tongues 10 to assume an operative position and to engage the long line, B, to connect the cross line thereto. It is to be observed that should the tension upon the long line or cross line be increased, the cross bar 7 is held in the crimps 105 110 with greater force and thus the possibility of the buckle slipping upon the long line is

effectually precluded. Should occasion require that the buckle be shifted to a new adjusted position upon the long line, such adjustment may be conveniently effected by 5 merely pushing the two lines rearwardly through the buckle frame, so as to provide a loop below the swinging end of the bail 6, whereupon the cross bar 7 is released and is adapted to be swung downwardly below the 10 crimped portions 5, to assume the position illustrated in dotted lines in Fig. 3, and thus move the tongues 10 into an inoperative position to release the long line, B. The long line is then drawn through the frame longitudinally as much as is required to shift the 15 frame to the new adjusted position thereon, the two lines being drawn forwardly to return the parts to their former positions.

From the foregoing description in connection with the accompanying drawing, it will 20 be apparent that I have provided an improved buckle which may be advantageously employed upon harness or the like, although not limited to any such use but susceptible of 25 application generally; which is capable of ready manipulation; which embodies to a marked degree the characteristics of simplicity, durability and strength, and which consists of comparatively few parts that may be 30 easily and cheaply manufactured.

Having thus described the invention, what I claim is:—

1. As a new article of manufacture, a buckle comprising a buckle frame including 35 side and end bars, and a bail pivotally connected to the side bars in proximity to one end bar of the buckle frame and provided at its pivoted end with a buckle tongue movable with the bail and adapted to be supported in operative relation to the said end 40

bar, the side bars being formed in proximity to the other end bar with open crimps, and the free end of the bail being designed to be seated in said crimps to maintain the buckle tongue in an operative position and being 45 arranged, in such position, short of the last named end bar, whereby to permit a strap to be passed through the bail and between the free end thereof and the corresponding end bar to retain the bail against swinging 50 movement.

2. As a new article of manufacture, a buckle comprising a buckle frame consisting of side and end bars, the side bars being formed in proximity to one end bar with 55 transversely registering bearing loops, and a bail mounted on one side of the frame and journaled in the bearing loops and provided at its pivoted end with a cross bar carrying a buckle tongue projecting through the 60 frame and movable on the opposite side thereof from the bail and adapted to be supported in operative relation to the said end bar, the side bars being formed intermediate of the loops and the other end bar with corresponding open crimps opening on the side 65 of the frame at which the bail is mounted, the free end of the bail being designed to be seated in the crimps to maintain the buckle tongue in an operative position, and being arranged, in such position, short of and in spaced relation to the corresponding end bar 70 of the frame.

In testimony whereof I affix my signature in presence of two witnesses.

HARVEY HALL. [L. S.]
